UNITED STATES PATENT OFFICE.

FOREST V. DETWILER, OF CHICAGO, ILLINOIS.

COOKING APPARATUS.

1,205,438.

Specification of Letters Patent. Patented Nov. 21, 1916.

Application filed July 11, 1914. Serial No. 850,388.

To all whom it may concern:

Be it known that I, FOREST V. DETWILER, a citizen of the United States, residing at Chicago, in the county of Cook and State of Illinois, have invented certain new and useful Improvements in Cooking Apparatus, of which the following is a specification.

This invention relates to improvements in cooking apparatus designed for the use of fluid fuel, and one of the objects of the same is to provide an improved portable device of this character, having means whereby different cooking operations may be simultaneously performed in different parts of the apparatus, and by the heat of a single burner, and means whereby the burner may be shifted to perform still another cooking operation.

A further object is to provide an improved device of this character having means whereby the circulation of the products of combustion from the burner may be readily controlled.

To the attainment of these ends, and the accomplishment of other new and useful objects as will appear, the invention consists in the features of novelty in substantially the construction, combination and arrangement of the several parts, hereinafter more fully described and claimed and shown in the accompanying drawings illustrating the invention, and in which—

Figure 1 is a vertical longitudinal sectional view of an improved device of this character constructed in accordance with the principles of this invention. Fig. 2 is a sectional view on line 2—2, Fig. 1. Fig. 3 is a sectional view taken on line 3—3, Fig. 1. Fig. 4 is a sectional view taken on line 4—4, Fig. 1. Fig. 5 is a sectional view taken on line 5—5, Fig. 1. Fig. 6 is a rear elevation of the oven portion of the apparatus. Fig. 7 is a sectional view taken on line 7, 7, Fig. 1. Fig. 8 is an enlarged detail view of a portion of one of the ovens and of the oven door. Fig. 9 is an enlarged detail sectional view of a portion of the apparatus showing the manner in which the joints are constructed. Fig. 10 is an enlarged detail sectional view of the damper mechanism, showing the means whereby the operation of one damper will automatically actuate the other damper. Fig. 11 is a detail perspective view of one of the ovens removed. Fig. 12 is a perspective view of the entire apparatus. Fig. 13 is an enlarged detail sectional view

of a modification showing the manner in which the kerosene burner may be employed in the apparatus.

Referring more particularly to the drawings, the stove proper comprises a portion forming a chamber 15 having a laterally extended portion 16, the walls 17 and the base 18 of the laterally extended portion being constructed in any suitable manner and of heat insulating material. The top 19 of the stove is constructed of heat insulating material and is provided with the usual stove openings 20, and a heat distributor or deflector 21 is supported by the top 19 above the burner 22, so that the products of combustion from the burner will strike the deflector and will be distributed to the stove holes.

The portion 15 of the stove is provided with air inlet openings 23 controlled by the dampers 24 by means of which the supply of air to the burner may be controlled and supports 25 are arranged within the chamber 15 for supporting a broiler 26 and a removable element 27.

The laterally projecting portion forming the chamber 16 of the stove proper is provided with an outlet opening 27 controlled by a damper 28, (see particularly Figs. 1 and 10), by means of which the products of combustion may pass through the outlet 27 into a flue 28^a and this flue 28^a has communication with a flue 29 leading to an outlet pipe 30, the flues and pipe serving as a means for carrying off the gases.

Arranged within the chamber 16 is an inclined wall or partition 31 which extends upwardly from a point adjacent the chamber 15 to the heat insulated wall 32, to form a narrow or restricted outlet 33. This outlet 33 is controlled by the damper 34 which is connected by means of a link 35 with the damper 28, so that when the latter is actuated by a handle from the front of the stove, to open the outlet 27, the damper 34 will be closed, and when the damper 28 is actuated to close the outlet 27, for a purpose to be hereinafter set forth, the damper 34 will be opened. The inclined wall 31 is preferably provided at its forward edge with an upwardly projecting wall or portion 36 and this forward edge of the wall may be anchored in any suitable manner such as by means of fastening devices 37. The object of the upwardly projecting wall 36 is to prevent any grease or liquid or any foreign

matter which may fall through the stove holes 20 from passing into the chamber 15 or to the burner 22.

A damper 38 is arranged between the 5 chambers 15 and 16 for controlling the products of combustion, and this damper is preferably slightly curved as shown, and extends across the communicating passage between the chambers, at a point between the stove holes. When it is desired to direct the products of combustion to one set of stove holes, the damper 38 is positioned as shown in Fig. 1 being controlled from the front of the apparatus by means of an actuating handle 39. 10 When it is desired to distribute the products of combustion to all of the stove holes, then the damper 38 is adjusted to the position shown in dotted lines in Fig. 1. The burner 22 is preferably of the reversible type and 15 is also removable, being removably supported in any suitable manner, such as by means of a bearing 40 formed in a partition 41, (see Figs. 2 and 3), in the stove, and also having a bearing in the front wall of the 20 stove. The mixing chamber 43 of the burner into which the nozzle 44 projects, the latter receiving its supply of fuel through the supply pipe 45, is provided with a sleeve portion 46 which extends through the bearing 42 so that the end of the burner 22 may 25 be telescoped thereinto, and a fastening device 47 secures the parts together. Thus when it is desired to remove the burner 22, the fastening device 47 is released, and the 30 mixing chamber 43 moved forwardly so as to disengage the end of the burner. Access may be had to the chamber 15 through a suitable closure 48 arranged beneath the burner for closing an entrance to the 35 chamber.

The burner 22 is preferably of a size to extend only part way across the chamber 15 and terminates short of the rear wall 49 of the chamber and a partition 50 is arranged transversely of the space between the 40 partition 41 and the wall 49 to form a chamber 51 having an entrance through the top thereof closed by a removable closure 52. Within this chamber 51 is arranged a water 45 coil 53 and the front wall 54 of the chamber 51 is provided with an entrance opening 55 adjacent the burner 22 and this opening is controlled by a damper 56 controlled by a handle 57 that extends through the side 50 of the apparatus.

When it is desired to direct the products of combustion into the chamber 51 to heat the coil, the damper 56 is opened and is preferably so arranged that it will extend a short 55 distance over the burner and when it is desired to close the entrance 55 to the products of combustion, the damper 56 is closed.

The rear wall 49 of the stove extends for some distance above the top 19 and a support or shelf 58 may be connected with this

wall. The partition wall 32, (see Fig. 1), also extends upwardly above the top 19 of the stove and preferably at right angles to the wall 49. This wall 32 forms one of the side walls of the ovens that preferably project above the top of the stove, the other side wall 59 resting upon an extended portion 18 of the chamber 16, and the back wall 60 of the oven compartment is offset in a direction forwardly of the wall 49 to form a space within which the flues 28, 29 and 30 are arranged (see particularly Figs. 6 and 12), and the flue 30 preferably projects a slight distance above the top 61 of the oven compartments. This compartment is provided with a front wall 62 having openings leading therethrough, preferably two openings and projecting into these openings are removable ovens 63, (see particularly Figs. 1, 8 and 11). These ovens are superposed 80 and are of a size somewhat less than the interior of the oven compartment so that when placed in position there will be formed flues or passage ways around the ovens and between the ovens and the respective walls of the compartment. These ovens 63 preferably comprise a body portion having a forward extremity 64 separate therefrom and secured thereto by means of fastening devices 65, and these extremities are provided 85 with flanges 66 that are adapted, when the ovens are inserted through the respective openings in the wall 66, to rest flat against the outer face of the wall, and the ovens are removably secured in position in any suitable manner such as by means of fastening devices 67 passing through the rear walls of the ovens and through the rear wall 60 of the compartment. If desired suitable supports 68 (see Fig. 1), may be provided for 90 the lower oven.

A closure 69 is provided for each of the ovens, and additional fastening devices 70, (see particularly Fig. 8), are provided for holding the ovens in position and these fastening devices pass through the flange 66, and are threaded into a collar 71 arranged in the rear of the wall 62. When it is desired to remove these ovens, all that is necessary is to remove the fastening devices 70, 75, 80, after the closures 69 have been opened and then draw the ovens out.

The lowermost oven which is supported by the supports 68, (see Fig. 1), forms a flue or passage 72 between its bottom and the wall 18, and also flues or passages 73, 74 between its side walls and the side walls of the oven compartment, and the upper oven is placed above the lower oven to form a flue or passage 25 between the ovens, flues 75 or passages 76, 77 between its sides and the sides of the oven compartment and a flue or passage 78 between its top and the top wall 61 of the oven compartment.

A partition 79 is arranged between the 130

wall 32 of the oven compartment and the lowermost oven to form the top of the flue 73, and a flue 80 is arranged between the wall 59 of the oven compartment and the adjacent wall of the upper oven near the bottom thereof to form a closure for the bottom of the flue 77. This flue 80 extends entirely across the passage and has an opening or inlet 81 through its upper wall, 5 which communicates with the flue 77, and this flue 80 has communication by means of a flue 82 arranged adjacent the back wall 60 of the oven compartment, and outside of the oven, with the flue or pipe 30, as shown 10 clearly in Figs. 1 and 6.

An outlet opening 83 leads from the flue 25 to the flue 29 and this outlet is controlled 25 by the damper 84, similar to the damper 27 and which damper 84 is controlled by 20 an operating handle 85 arranged at the front of the apparatus.

A damper 86 similar to the damper 34 is provided to close the entrance to the flue 76, the dampers 84 and 86 being connected 25 by means of a link 87 so that when the damper 84 is opened, the damper 86 will be closed and vice versa.

The operation of this portion of the apparatus is as follows: When it is desired to 30 use the stove holes and not the ovens, the damper 34 is closed and the damper 28 opened so that the products of combustion will pass out of the opening 27 into the flue 28^a, flue 29 and the outlet pipe 30, the 35 damper 84 being also closed. When it is desired to use the lowermost oven and not the upper oven, the damper 86 is closed and the damper 84 opened, while the damper 28 is closed and the damper 34 opened. This 40 will cause the products of combustion to flow into the flue or passage 73, thence into the flue or passage 72 under the lower oven, through the flue or passage 72, into the flue or passage 25 between the ovens, through 45 the openings 83 into the flue 29 and out of the flue 30. When it is desired to use both ovens, the damper 84 is adjusted to close the opening 83 and this will simultaneously adjust the damper 86 to open the passage 50 76. Then the products of combustion instead of passing through the opening 83 will flow into the flue or passage 76 through the flue or passage 78 thence into the flue or passage 77, into the flue or passage 80 55 through the opening 81, into the flue 82 and thence through the flue or pipe 30. Thus it will be manifest that the circulation of the products of combustion will be at all times absolutely under the control of the 60 operator.

When it is desired to employ kerosene as a fuel, the burner 22 may be removed in the manner already described and the broiler 26 and removable support 27 are also removed, 65 (see Figs. 1 and 13). After these parts

have been removed, a support 88 is placed in the chamber 15 to support the burner 89 which receives its supply through the pipe 90, the damper 24 controlling the openings 23 being closed. In order to supply air to 70 this burner 89, there is provided an inlet 91, arranged in the bottom 92 of the chamber 15, and which inlet is controlled by a closure 93, that is adapted to be open for this purpose and closed when the burner 22 is used. 75 When the burner 89 is not employed, the opening 94 through which the pipe 90 passes, is closed by a suitable closure 95.

The entire apparatus may be supported by means of suitable legs 96, and a suitable 80 support or shelf 98 may be provided beneath the ovens.

What is claimed as new is:—

1. A stove embodying a cooking top, an elevated oven adjacent thereto, a burner beneath the said top, a flue leading from the burner to the lower part of the oven, a damper controlling said flue, an outlet damper in said flue between the burner and said oven, and an operative connection between the dampers whereby the opening of one damper will close the other. 85

2. A stove embodying a cooking top, an elevated oven adjacent thereto, a burner beneath the said top, a flue leading from the burner to the lower part of the oven, said top forming one wall of the flue, the bottom of the flue being inclined and provided with an upwardly projecting wall to form a tray beneath the top, a damper controlling said flue, an outlet damper in said flue between the said oven and burner, and an operative connection between the dampers whereby the opening of one damper will close the other. 90

3. A stove embodying a cooking top, an elevated oven adjacent thereto, a burner beneath the said top, a flue leading from the burner to the lower part of the oven, a tapering deflector disposed above the burner, supported by and depending from the said cooking top, a damper controlling said flue, an outlet damper in said flue between the burner and said oven, and an operative connection between the dampers whereby the opening of one damper will close the other. 100

4. A stove embodying a cooking top, an elevated oven adjacent thereto, a burner beneath the said top, a flue leading from the burner to the lower part of the oven, a damper controlling said flue, an outlet damper in said flue between the burner and said oven, an operative connection between the dampers whereby the opening of one damper will close the other, and a combined 110 damper and deflector for controlling the inlet to the said flue. 120

5. A cooking apparatus embodying a burner chamber having stove holes in the top thereof, a burner in the chamber, an ele- 130

- vated oven compartment adjacent thereto, an outlet from the oven compartment, a flue leading from said burner chamber to the lower part of the oven compartment, a 5 damper for controlling the inlet to the oven compartment, an outlet from the burner chamber, and means responsive to the movement of the said damper for closing the said outlet of the burner chamber when the 10 damper is adjusted to open the inlet to the oven compartment, and for opening the outlet when the said damper is closed.
6. A cooking apparatus embodying a burner chamber having stove holes in the 15 top thereof, a burner in the chamber, an elevated oven compartment adjacent thereto, an outlet from the oven compartment, a flue leading from said burner chamber to the lower part of the oven compartment, a 20 damper for controlling the inlet to the oven compartment, an outlet from the burner chamber, a damper for controlling the outlet of the burner chamber, and means connecting the said dampers for operation in 25 unison and opposition to each other.
7. A cooking apparatus embodying an elevated oven compartment, a plurality of superposed oven chambers therein spaced from the walls of the compartment to form 30 flues about the ovens, and spaced from each other to form a flue therebetween, an outlet from the oven compartment, a damper for closing such outlet, a second damper for controlling the passage around one of the 35 ovens, means connecting the dampers for operation in unison and in opposition to each other, a second outlet leading from the said oven compartment and adapted to receive the heated air when the first recited 40 outlet is closed, and means for supplying heated air to the flues.
8. A cooking apparatus embodying an oven compartment, a plurality of ovens superposed therein and spaced from each 45 other to form a flue therebetween, an outlet leading from the oven compartment and having communication with the flue, a damper controlling the outlet, said ovens being spaced from the walls of the oven compartment to form flues completely therearound, 50 an outlet flue having communication with the last said flue, a damper for controlling

the flue around one of the ovens and located between the inlet of the said outlet flue and the first said damper, an inlet for 55 the heated air and leading into the compartment and communicating with the flue around one of the ovens, and means connecting the dampers for operation in unison, whereby when one is opened the other 60 will be closed.

9. A cooking apparatus embodying an oven compartment, a plurality of ovens superposed therein and spaced from each other to form a flue therebetween, an outlet 65 leading from the oven compartment and having communication with the flue, a damper controlling the outlet, said ovens being spaced from the walls of the oven compartment to form flues therearound, an outlet flue having communication with the last said flue, a damper for controlling the entrance to the flue around one of the ovens, and located between the inlet of the said outlet flue and the first said damper, an 70 inlet for heated air leading into the compartment and communicating with the flue around one of the ovens, means for connecting the dampers for operation in unison 75 whereby when one is opened the other will 80 be closed, and means removably securing the ovens in the compartment.

10. A cooking apparatus embodying a burner chamber having stove holes in the top thereof, an oven compartment having 85 communication with the burner chamber, said chamber and compartment being arranged side by side, the back of the oven compartment being disposed forwardly of the back of the burner chamber to form a 90 recess, and a flue extending along the back of the oven compartment exterior thereof, and arranged in the said recess, said flue having communication with the interior of the said chamber and compartment. 95

In testimony whereof I have signed my name to this specification, in the presence of two subscribing witnesses, on this 4th day of June A. D. 1914.
